UNITED STATES PATENT OFFICE

EDWARD O. TINSLEY, OF NEW YORK, N. Y., ASSIGNOR TO ROBERT GAIR COMPANY, OF NEW YORK, N. Y., A CORPORATION OF NEW YORK

TILT BOTTOM DISPLAY CONTAINER

Application filed March 28, 1925. Serial No. 19,066.

This invention relates to foldable containers or boxes formed by folding suitable material such as cardboard and has for its objects the provision of dual walls about the 5 container portion with the outer walls downwardly extended to form a display easel and a support for the container cover.

Another object of the invention is to provide a box of the kind which may be printed 10 in the flat on one side of the cardboard and which when set up will expose the printed and finished sides of the cardboard only.

Another object is to provide an efficient 15 foldable easel which will not collapse under load.

In the accompanying drawings,

Fig. 1 is a rear perspective view of the 20 assembled container;

Fig. 2 is a fragmental perspective view showing the container open;

Figs. 3 and 4 show the two blanks forming the container;

Fig. 5 is a plan view of the two blanks 25 assembled and folded flat for shipment and storage;

Fig. 6 is a fragmental perspective view of the container with the parts partially assembled.

Figs. 7 and 8 are bottom views showing 30 folded and partly folded positions of the easel; and

Fig. 9 is a perspective view showing the 35 easel in supporting position.

The blank, Fig. 3, comprises the front wall 7, the side walls 8 on the ends of the front wall 7, the rear wall 9 on an end of one of the side walls 8, the cover support 10 on the top edge of the rear wall 9, the joining flap 11, the triangular easel sides 12 on the bottom edges of the side walls 8, and the easel back connection on the bottom edge of the rear wall 9, the front, and rear walls and the easel back connection all being of the same length, and the easel sides being in length on one of their sides the same as the length of said side walls and the bases of the easel sides being in width the width of said easel back connection, said joining flap 11 being connected to an end of one of the

side walls 8 and the base of one of the easel sides 12 and being in length equal to the combined width of the adjacent side wall 8 and the length of the base of the adjacent easel side 12; the limits of the several parts 55 being defined by the broken lines, indicating scorings within the blank outline.

The blank, shown in Fig. 4, comprises a blank forming the bottom of the container 60 13 with extensions thereon forming the inner front wall 14, the two inner side walls 15, the inner rear wall 16, and in extension from said rear wall 16, the cover 17.

The blank shown in Fig. 3 is bent on the transverse scorings to form a rectangular 65 binding member or collar as shown by 7, 8, 9, 11, Figs. 2 and 6, with cover support 10 and the easel portions. The blank, shown in Fig. 4, is passed through this collar by folding down the inner sides 15, as shown in Fig. 5, until the rear inner wall 16 is superimposed on rear outer wall 9 in register on lines 18 and the two blanks are fastened by glue or staples. Sides 8 and front 7 are pressed down, as shown in Fig. 5, to form a compact shipping and storage unit. When it is desired to fill the container the front and outer side walls 7—8—8 are raised, as shown in Fig. 6 and the bottom 13 bent up, with inner side and front walls 14—15—15 70 75 raised, within the rectangular collar 7, 8, 9, 11. The filled containers can be closely packed for shipment by nesting the easel portion over the closed cover of the under-imposed container, the extensions of the outer side and rear walls being slightly tapered outwards for that purpose.

This method of assembling and positioning the several parts permits of printing the 80 85 blanks on one side and yet show all printed surfaces when the container is in opened display position as in Figs. 1 and 2.

When assembled as in Fig. 2, the display 90 95 container comprises the container portion including the rectangular bottom 13, and upstanding inner front, side and rear walls 14, 15 and 16 foldably connected at right angles to said bottom by the fold lines, the rear wall being extended to form the container cover 17 foldably connected by the fold line 18 100

with said rear wall. The binder member comprising a rim, band or collar is disposed around said container portion and forms an easel back and outer front, side and rear walls 5 7, 8 and 9 joined to each other at the corners by the fold lines and respectively disposed flat against the outer face of said inner front, side and rear walls 14, 15 and 16. The flap 11 foldably adjoining the end of one of the 10 outer walls 8 of the binder member is secured by staples, glue or otherwise to the free ended rear wall 9 of the binder member and the container portion is then inserted in the binder member as before stated and the flap 11 15 of said member is secured by staples, glue or otherwise to the rear wall 16 of the container portion, the flap 11 thus being interposed between the rear walls 9 and 16 and secured to both these walls, the walls of the binder 20 member cooperating with the walls of the container portion to form a double walled container the container portion of which is tensionally held in the binder member and supported therein by the flap 11, the bottom 25 13 of the container portion at its edge adjacent to the wall 16 being spaced away from the lower edge of the easel forming extension 19 of the binder member as seen in Figs. 1 and 2, the bottom 13 thus being spaced away 30 by equal distances from the top edges of the sides 7, 8 and 9 of the binder member and the top edges of the sides 14, 15 and 16 of the container portion being flush with the top edges of the sides 7, 8 and 9 of the binder 35 member, the bottom 13 at its edge adjacent to the rear wall of the binder member thus lying substantially in the plane of the lower edge of the wall 9, and at its edge adjacent to the front wall 7 being substantially in the 40 plane of the bottom edge of the wall 7. It will be noted that the joining flap 11 provides a rigid supporting means disposed between the rear sides of the binder member and container portion and extending from 45 the line of the flush top edges of the rear sides of the binder member and container portion to the bottom edge of the easel back extension of the binder member for maintaining the container portion at its rear side 50 in the binder member in the position above described, the container portion at its front side being supported in the position described by the tension of the binder member, the easel support at its rear or easel back connection 55 being stiffened by said flap against collapse.

The bottom edge of said outer front wall 7 terminates with the bottom edge of the inner front wall 14; but the rear outer wall 9 is extended both slightly above the inner rear wall 16 to form a cover support 10 for the cover 17, and a considerable distance downwardly below the container to form the rear easel member 19; while the outer side walls 8 are downwardly extended to form triangular easel sides 12, said sides terminating in a

straight edge joining the lower edges of the outer front wall and said rear easel member.

The rear member 19 and sides 12 may be stiff and unfoldable and nestable as above 70 stated, or they may be foldable flat against the bottom 13 for storing and shipping. In order that the member 19 and sides 12, may be easily changeable from folded to unfolded position, and may form a dependable easel 75 75 which will not collapse under load, these parts are folded and scored as will now be described.

To this end the rear easel member 19 has a fold line 25 (Figs. 7 to 9) at the bottom of 80 the container and tending to fold inward; while the easel sides 12 have lines of fold 26 at the bottom of the container permitting folding either inward or outward. The inner face of each of said sides 12 is provided 85 with a scoring defining a line of fold 27 extending from a rear corner of the container and substantially bisecting the upper rear angle of the easel side 12 and tending to assume a partly folded position as in Fig. 9. 90

Thus, when said easel member 19 is first folded flat against the bottom of the container 13 (Fig. 8), each of said easel sides 12 may be folded upon itself at said line 27 and then be turned to lie against the exposed 95 face of the rear easel member, as in Fig. 7, whereby when said rear easel member 19 is pulled outwardly from the bottom 13, said sides 12 will pass through the position of Fig. 8 and be forced outwardly or bulged 100 to the position 28 of Fig. 9 and be held in said slightly folded position. In this position, the said rear member 19 and sides 12 downwardly diverge and form a somewhat laterally extended base support for the 105 container, all portions of which tend, under direct downward pressure of a load in or on the container, to move outwardly, as far as possible without tearing, thus insuring an easel which will not collapse under load. 110

I claim as my invention:

1. In combination, a container; a support therefor comprising a rearwardly slanting rear easel member; and triangular easel sides downwardly extending below the container 115 and each joined to the rear member and slanting outwardly intermediately of its ends; the rear member being creased to give it a tendency to fold inwardly against the bottom of the container; the intermediate part of 120 the easel side being creased to give it a tendency to fold outwardly to assume a partly outwardly folded position whereby when said easel member is folded flat against the bottom of the container, each of said easel 125 sides may be folded upon itself and lie against the exposed face of the rear easel member.

2. In combination, a container; a support therefor comprising a rearwardly slanting 130

rear easel member extended downwardly below the container; and triangular easel sides downwardly extended below the container, each joined to the rear member and slanting 5 outwardly intermediately of its ends; each of said sides being provided with a line of fold extending from the upper rear corner of the easel side and substantially bisecting the upper rear angle of the easel side, said side at 10 said line being slightly folded outwardly and slanted outwardly, whereby said sides are disposed at an outward slanting angle outside of the downward geometric projection of the upper part of the easel; whereby 15 downward pressure upon the container will cause the bottom edge of the easel member and sides to tend to move outward and pull against each other to give a rigid support by the easel and tend to prevent the collapsing 20 of the easel under the container.

3. In combination, a container having side and rear walls; the rear wall being extended below the container to form a rear easel member having a fold line at the bottom of 25 the container; the side walls being extended below the container to form triangular easel sides joined to the rear easel member at the rear corners by fold lines and each having a line of fold at the bottom of the container 30 permitting folding both inwardly and outwardly; the inner face of each of said easel sides being provided with a scoring defining a line of fold extending from a rear corner of the container and substantially bisecting 35 the upper rear angle of the easel side and tending to fold outwardly only, to assume a partly folded position whereby when said easel member is folded flat against the bottom of the container, each of said easel sides 40 may be folded upon itself at said scoring and lie against the exposed face of the rear easel member; whereby when said rear easel member is pulled outwardly beyond the downward geometric projection of the container 45 bottom to an outward slanting angle, said sides will be forced outwardly and remain outwardly slanting outside of said projection; downward pressure upon the container causing the bottom edge of the easel member 50 and sides to tend to move outward and pull against each other and limit their movement to give a rigid support by the easel and to prevent pressure on the container from collapsing the easel under the container.

5. In combination, a container having side and rear walls; and a folded easel secured thereto including easel sides and a rear easel member forming continuations of the side and rear walls of the container, and joined to 60 each other at the rear of the sides by fold lines; the rear easel member having a fold line at the bottom of the container and being folded inwardly against the bottom of the container; the easel sides being triangular in shape and each having a line of fold at the

bottom of the container; the inner face of each of said easel sides being provided with a scoring defining a line of fold extending from a rear corner of the container and substantially bisecting the upper rear angle of the 70 easel side, each of said easel sides being folded flat upon itself at said scoring and lying against the exposed face of the rear easel member; whereby when said rear easel member is pulled outwardly beyond the 75 downward projection of the container bottom to an outward slanting angle, said sides will automatically be forced outwardly and remain outwardly slanting outside of the 80 downward geometric projection of the container bottom.

5. In combination, a supporting means, and a support therefor comprising a downwardly and rearwardly slanted rear easel member; and triangular easel sides downwardly 85 extended below the supporting means and each joined to the rear member and each of said sides being creased to give it a tendency to fold and slant outwardly intermediately of its ends.

6. In combination, a container; and a support therefor comprising a rearwardly slanting rear easel member, and triangular easel sides downwardly extended below the container and each joined to the rear member and each of the sides being creased to give it a tendency to fold and slant outwardly intermediately of its ends to render the support more rigid and to facilitate nesting.

Signed at New York, in the county of New 100 York and State of New York March, A. D. 1925.
